UNITED STATES PATENT OFFICE.

SAMUEL W. SUNDAY, OF TOPEKA, KANSAS.

DUST-SEPARATOR FOR STREET-SWEEPERS.

1,223,215.

Specification of Letters Patent. Patented Apr. 17, 1917.

Application filed January 21, 1916. Serial No. 73,424.

To all whom it may concern:

Be it known that I, SAMUEL W. SUNDAY, a citizen of the United States, residing at Topeka, in the county of Shawnee and State 5 of Kansas, have invented new and useful Improvements in Dust-Separators for Street-Sweepers, of which the following is a specification.

This invention relates to street sweepers 10 and it consists of the novel features herein-after described and claimed.

An object of the invention is to provide a street sweeping machine of such structure that the dirt which is removed from the 15 street by the brush will be deposited in one hopper and the dust laden air removed from the dirt as it is deposited in the said receptacle and conducted to another receptacle containing means for separating the dust 20 from the air, the last mentioned receptacle being adapted to collect or accumulate the dust. From the last mentioned receptacle the air is returned to the brush thereby creating a circulation within the machine and 25 making it practically dustless.

Another object of the invention is to provide a street sweeping machine which is simple of construction, easy to operate and economical to maintain in operative condition. 30

A still further object of the invention is to provide in a machine of the character indicated means for preventing the same from freezing in cold weather and thus preventing the possibility of the parts becoming clogged during the operation of the machine.

In the accompanying drawings:

Figure 1 is a side elevation of the street 40 sweeper.

Fig. 2 is a top plan view of the same with parts broken away.

Fig. 3 is a longitudinal sectional view of the same cut on the line 3-3 of Fig. 2.

The machine comprises a frame 1 the rear 45 part of which is supported upon traction wheels 2. Dirigible wheels 3 support the forward portion of the said frame and a suitable steering mechanism indicated in 50 general at 4 is operatively connected with the wheels 3 for directing the same.

An engine is mounted upon the rear portion of the frame 1 and its shaft 5 is journaled in suitable bearings mounted upon 55 the said frame as best shown in Fig. 1 of the drawing. A shaft 6 is journaled for ro-

tation on the rear portion of the frame 1. Sprocket wheels 7 are mounted upon the shaft 6 and sprocket wheels 8 are fixed with relation to the traction wheels 2. Sprocket chains 9 are trained around the sprocket wheels 7 and 8 and are adapted to transmit rotary movement from the shaft 6 to the wheels 2. Means are provided for rotating the shaft 6 from the engine shaft 5 and will 65 be now explained. A shaft 10 is journaled for rotation in bearings mounted in advance of the said engine and upon the frame 1 and a sprocket wheel 11 is fixed to the said shaft 10. A sprocket wheel 12 is mounted on the 70 shaft 5 and a sprocket chain 13 is trained around the sprocket wheels 11 and 12. The wheel 12 may be fixed to the shaft 5 by a clutch 12'. A sprocket wheel 14 best shown in Fig. 2 of the drawing is mounted upon 75 the shaft 10 and a sprocket wheel 15 is mounted upon the shaft 6. A sprocket chain 16 is trained around the sprocket wheels 14 and 15 and is adapted to transmit rotary movement from the shaft 10 to the shaft 6. 80 The chain 13 transmits rotary movement from the engine shaft 5 to the shaft 10.

A receptacle 17 is mounted at the forward portion of the frame 1 and an operator's seat 18 is mounted on the top of the said 85 receptacle. The receptacle 17 is provided at its bottom with an opening which is normally closed by a hinged door 19 best shown in Fig. 3 of the drawing. A casing 20 is mounted behind the receptacle 17 and 90 is inclined downwardly and rearwardly. The upper end of the said casing communicates with the interior of the receptacle 17 at the rear side thereof. A plate 21 connects the rear portion of the upper side of the 95 casing 20 with the frame 1 as shown in Fig. 3. A shield 22 depends from the frame 1 at the upper rear edge of the plate 21 as shown in said figure. Vertically disposed guides 23 depend from the sides of the 100 frame 1 at the forward edges of the shield 22 and bearings 24 are movably mounted in the said guides. Coil springs 25 bear at their upper ends against fixed parts of the guides 23 and at their lower ends against 105 the upper faces of the bearings 24 and are under tension with a tendency to normally hold the said bearings 24 resiliently on the lower portions of the said guides. A shaft 26 is journaled for rotation in the bearings 24 and carries a brush 27. A sprocket wheel 28 is fixed to the shaft 26 and a stub shaft 29

is journaled in suitable bearings mounted upon the frame 1. A sprocket wheel 30 is mounted upon the said stub shaft and a sprocket chain 31 is trained around the wheels 28 and 30. A gear wheel 32 is fixed 5 upon the stub shaft 29 and meshes with a gear wheel 33 loosely mounted on the shaft 10. A clutch member 34 is slidably mounted upon the shaft 10 but is constrained to rotate in unison with the same and is engageable with the side of the gear wheel 33 whereby the said gear wheel 33 may be caused to rotate with the shaft 10. A rod 35 is movably mounted in bearings provided 10 upon frame 1 and carries an arm 36 which engages the clutch member 34 and is adapted to move the said clutch member upon the shaft 9 as the rod 35 is moved. A bell crank lever 37 is fulcrumed upon the frame 1 and one end thereof is pivotally connected with one end of the rod 35. The other end of the bell crank lever 37 is pivotally connected with a rod 38 which extends longitudinally of the frame 1 and which is pivotally connected at its forward end with a lever 39 fulcrumed upon the machine in the vicinity of the operator's seat 18. It is apparent that by swinging the lever 39 the rod 38 will be moved longitudinally where- 20 25 30 35 40 45 50 55 60 65 70 75 80 85 90 95 100 105 110 115 120 125 130

by the bell crank lever 37 will be actuated and hence the rod 35 may be moved longitudinally to engage or disengage the clutch member 34 with the gear wheel 33. When the clutch member 34 is in engagement with the gear wheel 33 the said gear wheel rotates in unison with the shaft 10 whereby rotary movement is transmitted through the gear wheel 32 to the stub shaft 29 and through the chain 31 to the shaft 26 where- 20 25 30 35 40 45 50 55 60 65 70 75 80 85 90 95 100 105 110 115 120 125 130

by the said shaft and the brush 27 carried thereby are rotated. It will be observed that the arrangement of the parts is such that the brush 27 rotates in a counter clockwise direction as the machine moves in a forward direction over the surface of a street pavement.

Bell cranks are mounted upon the end portions of a shaft 41 which is turnably mounted upon the frame 1 and links 42 connect the lower ends of the said bell cranks 40 with the shaft 26. A rod 43 is pivotally connected at one end with the uppermost end of one of the bell cranks 40 and is extended longitudinally of the frame 1. The forward end of the rod 43 is pivotally connected with a lever 44 fulcrumed at the forward portion of the machine within convenient reach of one occupying the seat 18. It is apparent that by swinging the lever 44 the shaft 41 will be turned whereby the lower arms of the bell cranks 40 are swung and through the links 42 the shaft 26 may be raised against the tension of the spring 65 70 75 80 85 90 95 100 105 110 115 120 125 130

25 and thus the brush 27 may be lifted above the surface of the street or roadway. When the lever 44 is permitted to swing in a forward direction the links 42 and the springs 25 push the bearings 24 in a downward direction whereby the shaft 26 and brush 27 are resiliently held in their lowered positions.

A shaft 45 is journaled for rotation at the upper end of the casing 20 and a sprocket wheel 46 is mounted upon the end of the said shaft. A sprocket wheel 47 is mounted upon the shaft 10 and a sprocket chain 48 is trained around the sprocket wheels 46 and 47 and is adapted to transmit rotary movement from the shaft 10 to the shaft 45. A roller 49 is mounted upon the shaft 45 and is located within the upper end of the casing 20. Arms 50 (one of which is shown in Fig. 1) are pivotally connected at their upper ends with the shaft 45 and a roller 51 is journaled between the lower ends of the said arms. The said roller 51 is provided at its ends with wheels 52 which are adapted to travel upon the surface of the street or roadway when the arms 50 are at their lowermost position. A plate 53 is supported upon the shaft of the roller 51 and is located in advance of the lower forward portion of the brush 27. A belt 54 is trained around the rollers 49 and 51 and is provided upon its outer side with slats 55. Therefore it will be seen that as the roller 49 is rotated the belt 54 is moved longitudinally in the casings 20 and the upper run of the said belt moves in an upward direction. As the brush 27 encounters the loose material at the surface of the street or roadway it is swept up along the plate 53 and deposited upon the upper run of the belt 54 which carries it up and casts it into the receptacle 17. Links 56 are pivotally connected at their lower ends with the shaft of the roller 51 and their upper ends are pivotally connected with the lower arms of the bell cranks 40 at the same point at which the upper ends of the links 42 are connected with the said bell cranks. When the lower arms of the bell cranks 40 are swung in an upward direction as hereinbefore described the links 56 will raise the wheels 52 above the surface of the street or roadway, consequently the said wheels are raised or lowered at the same time that the brush 27 is raised or lowered.

A hood 57 is pivotally connected with the upper rear portion of the receptacle 17 and its rear end normally lies over a receptacle 58 mounted on the frame 1 behind the receptacle 17. The rear portion of the hood 57 normally incloses a fan 59 and the discharge outlet 60 of the said fan 59 is located in the receptacle 58. Baffle plates 61 and 62 are located in the upper portion of the receptacle 58 opposite the outlet 60. The plate 61 is imperforate while the plate 62

62 is perforated. The plate 62 is located between the plate 61 and the outlet 60. A plate 63 is mounted in the lower portion of the receptacle 58 and the intermediate part 5 of the plate 63 is spaced from the bottom of the said receptacle as best shown in Fig. 3 of the drawing. A water tank 64 is located behind the receptacle 58 and in advance of the engine and the exhaust pipe 65 from the engine passes through the upper portion of the tank 64 and then extends through the lower part of the rear side of the receptacle 58 and terminates under the plate 63. A pipe 66 leads from the upper portion of the receptacle 58 from a point in advance of the plate 61 and extends down through the plate 63 and the bottom of the receptacle 58 and terminates at its lower end at the rear portion of the brush 27 and 20 in front of the intermediate portion of the shield 22.

A pump 67 is mounted adjacent the tank 64 and its rotor is mounted upon the shaft 10 which passes through the casing of the said pump. A pipe 68 is connected at one end with the lower portion of the tank 64 and at its other end with the lower portion of the casing of the pump 67. The pipe 68 is provided with a valve 69. A pipe 70 is connected at 30 one end with the upper portion of the casing of the pump 67 and the other end of the said pipe 70 is located in the receptacle 58 just in advance of the discharge outlet 60 of the fan casing 59. The tank 64 is provided with a suitable quantity of water which may be poured into the same through the inlet 71 provided at the top of the said tank.

When the engine is in operation the exhaust is permitted to pass therefrom through the pipe 65 and as the exhaust passes through that part of the said pipe which is in the upper portion of the tank 64, sufficient heat is given off to prevent the water contained 40 within the said tank from freezing. From the exhaust pipe 65 the exhaust gases are discharged into the lower portion of the receptacle 58 below the plate 63 and thus the heat from the exhaust gases prevents the 45 contents of the said receptacle 58 from freezing. Furthermore the heat from the exhaust gases will serve to dry the material which is deposited within the receptacle 58 as is hereinafter explained.

50 During the operation of the sweeper the sweepings are engaged by the brush 27 and cast up along the plate 53 upon the upper run of the belt 54. The belt 54 carries the said material up into the receptacle 17 and the heavier particles gravitate into the lower portion of the receptacle. At the same time the fan 59 is in operation and the dust laden air is drawn from the upper portion of the receptacle 17 through the hood 57 and into 55 the fan. This dust laden air is discharged

from the outlet 60 into the receptacle 58. At the same time the pump 67 forces water which is received from the tank 64 through the pipe 70 and the said water is discharged in advance of the outlet opening 60. As the water comes in contact with the dust laden air the particles of dust are dampened and some of the water is sprayed upon the perforated plate 62. Those particles of dust which might escape the spray of water from the end of the pipe 70 will come in contact with the water which is deposited upon the plate 62 and therefore the said dampened particles of dust will gravitate down and deposit upon the plate 63 of the lower portion of the receptacle 58. As hereinbefore explained the heated gases which are exhausted from the engine through the pipe 65 will prevent the material in the lower portion of the receptacle 58 from freezing 60 and the heat from the said gases will also serve as a means for drying the material which is deposited upon the plate 63. The air which is admitted into the receptacle 58 as described, is permitted to pass therefrom through the pipe 66 and is discharged in advance of the intermediate portion of the shield 22 and immediately behind the brush 27 and thus should any particles of dust follow the air which passes through the pipe 66 they will be caught up by the brush and again passed through the sweeper along the course just described.

From the foregoing description taken in conjunction with the accompanying drawings it will be seen that a street sweeping machine of simple and durable structure is provided and that the same is capable of separating the dust laden air from the heavier material constituting the sweepings 105 and that the said dust laden air is relieved of the dust which is collected in the receptacle and furthermore means are provided for preventing the agent which serves to precipitate the dust from freezing in the machine and also the exhaust from the engine is utilized for the purpose of preventing the agent, which in this instance is water, from freezing in the tank which is employed for holding the same preparatory to its use for 110 sprinkling in the dust receptacle to precipitate the dust.

It is to be understood that various changes in form, proportion and minor details of construction may be resorted to within the 120 scope of the invention as claimed and that the structure may be varied within the limits stated.

Having described the invention what is claimed is:

In a machine of the character described a receptacle, means for depositing material in the receptacle, a fan for drawing dust laden air from the receptacle, a second receptacle which receives the discharge outlet 130

of the fan, a perforated plate located in the last mentioned receptacle opposite the discharge outlet of the fan, means for discharging water into the last mentioned receptacle at a point between the discharge outlet of the fan and the perforated plate, a plate located in the lower portion of the last mentioned receptacle and means for discharging a heating agent into the last men-

tioned receptacle and under the last mentioned plate.

In testimony whereof I affix my signature in presence of two witnesses.

SAMUEL W. SUNDAY.
